US0D1103430S

(12) **United States Design Patent** (10) **Patent No.:** **US D1,103,430 S**
(45) **Date of Patent:** **** Nov. 25, 2025**

(54) **CULTIVATED STONE SLAB**

(71) Applicant: **A&A Green Phoenix Group Joint Stock Company**, Hanoi (VN)

(72) Inventor: **Nang Xuan Ho**, Hanoi (VN)

(73) Assignee: **A&A Green Phoenix Group Joint Stock Company**, Hanoi (VN)

(**) Term: **15 Years**

(21) Appl. No.: **29/905,910**

(22) Filed: **Oct. 27, 2023**

(51) LOC (15) Cl. **25-01**

(52) U.S. Cl.

USPC **D25/151**; D25/138
